CLAIM

The ornamental design of a holder for retaining small metal objects magnetically, as shown and described.

DESCRIPTION

FIG. 1 is a perspective view of a holder for retaining small metal objects magnetically showing my new design in a closed condition;

FIG. 2 is a side elevational view;

FIG. 3 is a front elevational view;

FIG. 4 is a top plan view;

FIG. 5 is a rear elevational view;

FIG. 6 is a bottom plan view;

FIG. 7 is a perspective view of my design in an open-end condition;

FIG. 8 is a side elevational view of FIG. 7;

FIG. 9 is a front elevational view of FIG. 7;

FIG. 10 is a top plan view of FIG. 7;

FIG. 11 is a rear elevational view of FIG. 7; and

FIG. 12 is a bottom plan view of FIG. 7.
